(No Model.)

R. S. JENNINGS.
Railroad Signaling.

No. 240,594.

Patented April 26, 1881.

UNITED STATES PATENT OFFICE.

RALPH S. JENNINGS, OF BALTIMORE, MARYLAND.

RAILROAD-SIGNALING.

SPECIFICATION forming part of Letters Patent No. 240,594, dated April 26, 1881.

Application filed March 2, 1881. (No model.)

To all whom it may concern:

Be it known that I, RALPH S. JENNINGS, a citizen of the United States, residing at Baltimore, in the county of Baltimore and State 5 of Maryland, have invented certain new and useful Improvements in Railroad-Signaling; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 Figure 1 is a side view of my invention. Fig. 2 is an end view, showing it applied to an elevated railway. Fig. 3 is a perspective view of the lever which is attached to the locomotive for operating the valves, and Fig.

20 4 is a perspective view of a pair of the valves. The design of my invention is to signal when a train enters a section of a railroad and when it leaves said section for the purpose of indicating to the train following that 25 the section ahead is "blocked" or occupied by a train, or clear, as the case may be; to which end it consists, principally, in lighting and extinguishing the lamp by the passing train, whereby a signal may be set at the beginning of a section when the train has passed the end of said section.

30 My invention also consists in the arrangement of the gas pipes and valves in relation to the beginning and ending of the sections, 35 whereby the gas is turned off when a train enters the section and turned on when it leaves said section, the same being carried on continuously and automatically by each passing train.

40 It also consists in the arrangement, construction, and combination of the gas-pipes, valves, operating-lever, and other mechanical means for signaling, as will be hereinafter specified and claimed.

45 Referring to the drawings, A represents a lamp at the beginning of a section, and B another lamp at the beginning of another section and at the ending of the first section.

50 C represent star-wheels, which are connected with the valves b a' b', which are arranged near the tracks of the railroad, so as to be operated or turned one-quarter way round

when struck by the operating rod or lever D, which is attached to the locomotive, and may be so arranged as to be under the control of 55 the engineer; or it may be an immovable fixture on the engine. The star-wheels C and cocks or valves are arranged in double pairs at or near the beginning of each section, and the pairs at the beginning and ending of each 60 section are connected with independent gas-pipes F G, which are supplied from the main E. These gas-pipes and valves are arranged preferably as shown in Fig. 1. The lamps at each section are provided when in use with an 65 uninterrupted gas-lighting device, preferably an electric one, which is supplied with a current by the wire c, though it is evident that other devices for lighting the burners may be used, such as a small and imperceptible flame 70 near the burner.

In practice this invention may be used as follows: The lamps at all the sections are lighted, showing that the track is clear, the valves on the gas-pipes F G being arranged 75 thus: first pair at the beginning of a section, b closed, a open; second pair at the end of a section, a' open, b' closed, thus allowing a free flow of gas from the main E to the lamp A through the pipe F and valves a a'. When 80 a train enters on the section it turns the valves b a one-quarter way round and opens b and closes a, thus extinguishing the light at A. The train is now supposed to be on the section, and the light at A being out it will indicate 85 to the following train that the section in front is occupied or blocked. When a train is leaving the section it turns the valves a' b' one-quarter way round and leaves a' closed and b' open, thus lighting the lamp A by allowing 90 the gas to flow from the main through the pipe G and valves b' b. The same operation as hereinbefore described is performed by each train following.

If desirable, on roads where the beginning 95 and ending of the sections are not indicated the valves may be arranged to operate so as to light the lamps at the beginning of a section to indicate that that section is blocked, and to put the lamp out when the track is 100 clear.

What I claim as new is—

1. A system of railway-signaling substantially as herein described, the same consisting

in providing a motor or train with a valve-operating mechanism and in arranging gas-pipes with valves in proximity and relation to the railway-track, so that the aforesaid train in passing will operate the valves so as to cause a signal to be unset or set when the train enters a section, and to set or unset the signal when the train leaves the section.

2. An automatic system of signaling for indicating when a train enters and leaves a section of a railway, embracing the following elements: a motor or train provided with a valve-operating mechanism, a series of gas-pipes having valves arranged as shown, and lamps provided with a gas-lighting device, substantially as described and shown.

3. The combination, with a valve-operating mechanism arranged upon a railway-engine, a series of gas-pipes provided with valves lo-

cated at certain points on the railroad or sections, and arranged so as to be acted upon by the passing of the engine so as to light a lamp at the beginning of a section when a train has passed the end of said section, or vice versa, substantially as described, and for the purpose set forth.

4. In combination with a railroad-engine having a valve-operating mechanism attached thereto, a series of valves arranged upon gas-pipes as shown, and provided with star-wheels 30 C C, for the purpose set forth.

In testimony whereof I affix my signature in presence of two witnesses.

RALPH S. JENNINGS.
